UNITED STATES PATENT OFFICE.

ELIZABETH COOK, OF SALT LAKE CITY, UTAH.

HAIR CURLER.

Application filed October 15, 1924. Serial No. 743,678.

To all whom it may concern:

Be it known that I, ELIZABETH COOK, a citizen of the United States, residing at Salt Lake City, in the county of Salt Lake and State of Utah, have invented a certain new and useful Improvement in Hair Curlers, of which the following is a specification.

This invention relates more particularly to such hair curling devices as are applied to the hair by women and girls before retiring and the object of the invention is to provide an improved construction of such device whereby it may be more expeditiously applied and with better effect than those heretofore proposed.

The invention is embodied in the example herein shown and described, the features of novelty being finally claimed.

In the accompanying drawing—
20 Figure 1 is a front elevation of the device in opened condition.

Fig. 2 is a section on the line II—II, Fig. 1.

Fig. 3 illustrates the rolled up and secured condition of the curler such as when applied to a lock of hair.

Fig. 4 is a cross sectional view of a rolled up curler showing how the projecting ends of the rolling member bind the curler apron from slipping or unrolling.

In the views 5 designates a flexible strip or apron of woven fabric, preferably linen, of oblong form and which if for use on "bobbed" hair can be in the neighborhood of two and a half inches wide and three and a half inches long. At one end the strip 5 has attached to or formed with it by suitable stitching or otherwise a tube or casing 6 of fabric somewhat longer than the width 40 of the strip 5 so as to extend at each end beyond the edges of said strip; and in said tube is permanently confined by stitching the ends of the pocket a flexible but inelastic strip of metal 7 such for example as soft copper or lead or a suitable alloy of either of them adapted to be easily bent and to remain bent until purposely unbent by the

fingers of the hand. The end of the curler containing the strip 7 can be denominated the rolling end of the curler because the 50 other end is held while said end is rolled up toward it. At the other end of the strip 5 is formed by stitching a casing or hem 8 in which is confined by stitching, as before, a stiffening member 9 preferably of flat 55 metal or for example a doubled piece of stiff wire of hair pin form adapted to retain its form. The member 7 referred to is preferably wider than thick to facilitate starting the curling operation.

The mode of use is as follows: A lock of the hair is laid spread out on the strip 5 extended, as shown in Fig. 1, with the ends of the hair terminating near the hem at the bottom and the strip and lock rolled or folded over and over compactly together until the top member or binding 8 is reached, after which the projecting ends of the pocket and strip 7 are bent over onto the roll as depicted in Fig. 3 preferably just 65 below the pocket containing the stiffening member 9 as shown in Fig. 4 thus firmly binding together the rolled curler until it is desired to remove it at which time the binding end or ends are bent up and the 75 curler removed.

The forms of the parts can be changed without departing from the gist of the invention as claimed.

What I claim is:

A hair curler composed of a flexible apron of substantially rectangular form, a flexible non-resilient rolling member secured along one end of said apron and normally extending in the plane thereof beyond the 80 edge of the apron and a stiffening member secured along the other end of said apron and parallelly adjacent which stiffening member the aforesaid extending end of the rolling member is bendable to lie when the 85 curler is rolled up to cooperate therewith to prevent unrolling of the curler.

ELIZABETH COOK.
